COMBINED WALL RACK AND CONDIMENT DISPENSER

Doris Ann Hansen, Duluth, Minn.

Application May 12, 1954, Serial No. 30,418

Term of patent 7 years

(Cl. D44—22)

FIG. 2

Fig. 1 is a front elevational view of combined wall rack and condiment dispenser showing my new design.

Fig. 2 is a side elevational view thereof.

Fig. 3 is a sectional view on the line 3—3 Fig. 1. The dispenser member is of circular cross-section.

I claim:

The ornamental design for combined wall rack and condiment dispenser, substantially as shown and described.
